UNITED STATES PATENT OFFICE.

DE WANE B. SMITH, OF UTICA, NEW YORK.

STRAINER AND VALVE BOX FOR PUMPS OR THE LIKE.

1,297,603.

Specification of Letters Patent. Patented Mar. 18, 1919.

Application filed November 7, 1917. Serial No. 200,652.

To all whom it may concern:

Be it known that I, DE WANE B. SMITH, a citizen of the United States, and a resident of Utica, N. Y., in the county of Oneida and State of New York, have invented certain new and useful Improvements in Strainer and Valve Boxes for Pumps or the like; and I do hereby declare that the following is a full, clear, and exact description thereof, which will enable others skilled in the art to which it appertains to make and use the same, reference being had to the accompanying drawings, and to the reference numerals marked thereon, which form part 15 of this specification.

My present invention relates to sprayers and force pumps such as are especially adapted for use as a foot-held hand-operated bucket pump or sprayer.

20 The purpose of my invention is to provide an improved article of the class described which is simple and economical in construction and durable in use.

A further purpose is to provide a force 25 pump or sprayer that is especially adapted for domestic and agricultural purposes, in that the device is of such construction that it is ready for instant use and may be kept in workable condition with the minimum of 30 care.

A still further object of my invention is to provide an article of the class described of which the character, construction and combination is such that the device may be 35 manufactured or constructed from standard material with the use of very little expert labor and with a minimum of special parts.

My invention further resides in the particular construction of the parts of the device and the arrangement and combination 40 thereof as hereinafter set forth.

Further purposes and objects of my invention will appear from the specification and claims herein.

45 Figure 1 is a perspective view of a sprayer or force pump embodying my invention.

Fig. 2 is a longitudinal sectional view on an enlarged scale of the device shown in 50 Fig. 1, with the central part of the cylinder and air chamber and contained parts cut away in order to show the material parts upon a larger scale.

Referring to the drawings in a more particular description, it will be seen that the 55 force pump or sprayer therein shown comprises a pump cylinder 3 and an air chamber 4 both relatively long and conveniently constructed of thin sheet metal or tubing. Preferably the air chamber 4 is shorter and 60 of smaller cross area than the pump cylinder 3. Preferably also the air chamber will be secured to one side of the cylinder intermediate its ends, that is, with the cylinder extending both above and below the top and 65 bottom of the air chamber.

Reciprocatingly mounted in the pump cylinder 3 there is provided the piston 5 secured to the lower end of a piston rod 6 which projects upward from the piston 70 through the cylinder and beyond the upper end of the cylinder. To the upper end of the piston rod 6 is fastened the handle 7, whereby the device is operated. A wooden plug 8 is inserted in the upper end of the 75 cylinder 3 to form a plug to close said upper end of the cylinder and to guide the upper end of the piston rod 6. A centrally arranged aperture 9 is provided in the plug 8 to permit the passage of the piston rod 80 through the upper end of the cylinder. The aperture 9 is of such diameter as to fit the piston rod 6 close enough to prevent liquid from following the piston rod up through the plug, but is large enough to 85 allow free movement of the piston rod through said plug. The advantage of the wooden plug is that it provides an ample 90 guide for the piston rod that will not wear against the piston rod and that will be substantially without noise when the pump is being operated. The plug 8 is removably held in place by means of screws 10 fastened through holes near the upper end of the cylinder into the plug. A metal top 95 cap 11 may be provided to cover the top of the plug 8 and that portion of its sides that are above the cylinder. A central opening 12 will be provided in this top cap corresponding in location with the plug aperture 9, but a trifle larger. A collar or other enlargement 13 is provided upon the piston rod 6 a little below the handle 7 and at such a point upon the piston rod as to stop 100 downward movement of the piston rod before the piston 5 reaches the bottom of the

cylinder. This stop prevents the piston from damaging the strainer 14 provided in the lower part of the cylinder and also prevents the piston from being injured by contact with said strainer. This stop also insures sufficient space below the downward position of the handle 7 and the top cap of the pump to prevent the operator's hand being pinched at the end of the downward stroke. A similar collar or other enlargement 15 is provided upon the piston rod 6 a little ways above the piston 5. This collar acts as a stop to prevent the operator drawing the piston too far up and to prevent contact of the piston with the plug 8. Preferably the stop 15 will be located about two inches above the piston 5, thereby keeping the piston two inches or more from the upper end of the cylinder even at the upward end of its stroke. In this way the device is protected from undue side strain and the piston rod is prevented from being cramped sidewise as the operator starts the downward stroke.

25 The piston 5 may be conveniently constructed of two oppositely cupped leather washers 16 and 17 held in extended position between two slightly smaller and similarly cupped metal disks 18 and 19. The piston is conveniently and removably mounted upon the end of the piston rod by being held between an upper nut 20 first placed upon the piston rod and a lower nut 21 placed upon the piston rod after the washers and cupped plates have been placed in position upon the piston rod.

40 To the bottom of the cylinder 3 is affixed a short extension 22 having a coarse screw thread upon its side and having a narrow in-turned flange 23 at its bottom. Removably screw threaded on to the extension 22 is the bottom cap 24, which has interior screw threading at its upper end to fit the screw threading of extension 22. Near the bottom of said bottom cap 24 there are provided apertures 25 for the entrance of the water or other fluid to be pumped or sprayed by the device. Spaced from the in-turned flange 23 of the extension 22 there is provided upon the bottom cap 24 an inwardly extending shoulder 26. This affords a support for a centrally apertured disk 27 as of metal or other stiff material, upon which rests a rubber or leather washer 28 also 55 centrally apertured to form the valve seat of an upwardly opening check valve. The other member of said valve is a ball 29 of suitable material and of such size as to loosely fit into and cover the aperture in the 60 valve seat 28.

Just above the strainer 14 a port 30 is provided extending from the cylinder 3 into the lower end of the adjacent air chamber 4. A short distance above the bottom end

31 of the air chamber 4 is affixed a metal 65 plate 32 which serves as the valve seat of a check valve the other member of which is a loose ball 33 seating into the central aperture of the plate 32.

The outlet pipe 34 extends from a short 70 distance above the top 35 of the air chamber down through said air chamber top 35 and then down longitudinally through said air chamber to a point slightly above the top of the ball 33 when said ball is in seated 75 position. To the lower end of the outlet pipe 34 is affixed a plate 36 centrally apertured to correspond with the opening of pipe 34. Ample passage is afforded past plate 36 by means of said plate either being spaced from 80 the sides of the chamber or by being provided with notches or perforations in said plate whereby the water or other liquid may rise past the lower end of said outlet pipe. Preferably also one or more openings 85 38 are provided in the sides of said pipe 34 near its lower end but above the plate 36. The plate 36 operates to maintain the outlet 90 pipe 34 in the desired position in the air chamber 4 and thus prevents straining the joint made where the outlet pipe passes through the upper end 35 of the air chamber. The plate 36 also limits the upward movement of the valve ball 33 and prevents its being caught between the lower end of outlet pipe 34 and the adjacent walls of the air chamber. 4. The upper or exterior end of the outlet 34 is provided with an enlargement or shoulder 39 whereby a piece of hose 40 may be readily and securely but removably attached to the sprayer or pump. 100

A supporting bracket 41 has its upper end rigidly attached to the device as by being fastened to the side of the cylinder 3 and preferably reinforced by a band 42 partly 105 encircling said cylinder. From such point of attachment to the device the supporting bracket 41 extends out a short distance from the device and then longitudinally thereof to a point beyond the lower end of the pump. 110 At its lower end the bracket 41 is preferably extended outwardly at right angles. Such extension has fastened thereto a wider foot piece 43.

The pump or sprayer is placed in position 115 for operation by placing the lower end of the pump into a bucket or pail (not shown) with the supporting bracket of the device outside the pail and with the foot piece 43 upon the ground or floor upon which rests 120 the bucket. The operator then holds the sprayer in this position by simply placing one foot over the foot piece 43.

The pump is operated by the operator 125 grasping the handle 7 with one hand and working said handle up and down while with the other hand the operator may if desired hold the hose 42 or nozzle thereof and so

irect the spray or stream from the pump or sprayer.

It will be seen that upward movement of the piston 5 will close the check valve in the air chamber, preventing the return of the liquid that has passed said check valve and will open the check valve in the bottom of the pump cylinder, whereupon the liquid will pass said last check valve into the bottom of the pump cylinder and well up into the cylinder according to the extent of motion given the piston. The following downward stroke of the piston will put pressure upon the liquid therebelow and cause the check valve at the bottom of the pump cylinder to close and will force the liquid out from the pump cylinder through the port 30 into the part of the air chamber below the plate 32, whereupon the valve ball 33 will be raised and the liquid will be forced into the air chamber 4. Some of the liquid so entering will be forced directly out through the outlet pipe 34 and the balance of the liquid will be forced upward in the air chamber past the lower end of the outlet pipe 34 and well up into the upper part of the air chamber 4. This accumulation of liquid in an obvious manner compresses the air present thereabove in the air chamber, resulting in said liquid being expelled from the air chamber and through the outlet pipe 34 while the piston is taking its next upward stroke and while the valve ball 33 is closed therefor.

It will be seen that I have produced a form of force pump or sprayer that is very simple in construction and operation, and so adapted to be operated, cleaned or repaired by anyone usually required to handle such devices. It will be seen also that the general construction is of such character that very few special parts are used or parts that require complicated machinery for their construction.

It will be especially noted that the bottom cap 24 is adapted to be readily removed by being unscrewed from the extension 22. Thereupon access is had to the bottom end of the cylinder and to the lower side of the strainer 14, whereby those parts may be easily cleaned. At the same time the disk 7 and the rubber or leather washer 28 thereabove may be readily removed from their position in the bottom cap for cleaning or renewal and access thus had to the inside of the bottom part of said cap. This is a special advantage in force pumps used for domestic or agricultural purposes and for sprayers, in that the solid matter or sediment that sometimes accumulates may be cleaned away from the parts of the pump and the pump rendered fit for further use or left clean to put away.

By removing the screws 10 that extend through the cylinder into the wooden plug 8

and then removing the plug from the end of the cylinder, the piston 5 is readily removed from the cylinder. By removing the lower nut 21 of the piston the lower cupped disk 19 may be removed and then the two leather washers 16 and 17 can be readily removed from the piston rod for cleaning, repair or renewal. These parts may then be replaced into proper position in an obvious manner.

What I claim as new and desire to secure by Letters Patent is:

1. A removable strainer and valve box for the inlet of a pump or the like comprising an inlet extension on the pump, a cap detachably secured at its inner end onto said inlet extension and provided therebeyond with inlet ports, an inwardly extending shoulder within said cap intermediate its ends, a valve seat member located and held in place between the bottom of the pump extension and the shoulder of the said cap and a check valve member seating upon said valve seat member whereby the valve seat and valve member may be removed upon the removal of said cap.

2. A removable strainer and valve box for the inlet of a pump or the like comprising an inlet extension on the pump, a cap detachably secured at its inner end onto said inlet extension and provided therebeyond with inlet ports, an inwardly extending shoulder within said cap intermediate its ends, a valve seat member located and held in place between the bottom of the pump extension and the shoulder of the said cap, a check valve member seating upon said valve seat member and a strainer above the raised position of said movable valve member whereby the valve seat and valve member may be removed and access had to said strainer upon the removal of said cap.

3. A removable strainer and valve box for the inlet of a pump or the like comprising an externally-screw-threaded inlet extension on the pump, a cap screw-threaded at its inner end onto said inlet extension and provided therebeyond with inlet ports, an inwardly extending shoulder within said cap intermediate its ends, a valve seat member located and held in place between the bottom of the pump extension and the shoulder of said cap and a check valve member seating upon said valve seat member.

4. A removable strainer and valve box for the inlet of a pump or the like comprising an externally-screw-threaded inlet extension on the pump provided at its inner end with an inwardly extending flange, a cap screw-threaded at its inner end onto said inlet extension and provided therebeyond with inlet ports, an inwardly extending shoulder within said cap intermediate its ends, a valve seat member located and held in place between the inwardly extending flange at the bottom

of said extension and the shoulder of said cap and a check valve member seating upon said valve seat member.

5. A removable strainer box for the inlet of a pump or the like comprising an externally-screw-threaded inlet extension on the pump, a strainer near the inner end of said extension and a cap screw-threaded at its

inner end onto said inlet extension and provided therebeyond with lateral ports and an imperforate bottom forming a rest for the pump.

In witness whereof I have affixed my signature, this 16th day of October, 1917.

DE WANE B. SMITH.
